(57) **CLAIM**

The ornamental design for a grip of conduit dredge, as shown and described.

DESCRIPTION

FIG. 1 is a perspective view of a grip of conduit dredge, showing my new design;

FIG. 2 is an another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an operational perspective view thereof in an environment of use, in which the grip of conduit dredge combined with a spring of conduit dredge.

The broken lines shown are included for the purpose of illustrating unclaimed portions of the article and form no part of the claimed design.

1 Claim, 9 Drawing Sheets
